UNITED STATES PATENT OFFICE.

LOUIS A. LARSON, OF OSAKIS, MINNESOTA.

WAGON-SEAT.

1,074,960.

Specification of Letters Patent.

Patented Oct. 7, 1913.

Application filed April 12, 1913. Serial No. 760,638.

To all whom it may concern:

Be it known that I, LOUIS A. LARSON, a citizen of the United States, residing at OSAKIS, in the county of Douglas and State 5 of Minnesota, have invented certain new and useful Improvements in Wagon-Seats; and I do hereby declare the following to be a full, clear, and exact description of the invention, such as will enable others skilled 10 in the art to which it appertains to make and use the same.

My invention relates to improvements in wagon seats and, to this end, it consists of the novel devices and combinations of 15 devices hereinafter described and defined in the claims.

In the accompanying drawings, which illustrate the invention, like characters indicate like parts throughout the several views. 20 Referring to the drawings: Figure 1 is a view in front elevation of my improved wagon seat suspended within a wagon box from the wagon top box, said wagon boxes being shown in section; Fig. 2 is a view 25 corresponding to Fig. 1, with the exception that the wagon seat is supported in a different position from the top box, some parts being broken away and other parts being removed; Fig. 3 is an end elevation of the 30 wagon seat, as shown in Fig. 1, with the exception that certain parts are shown in different positions, by means of dotted lines; and Fig. 4 is a plan view of the wagon 35 seat, as shown in Fig. 3, with the exception that the back is shown in a folded position and certain other parts are indicated by dotted lines.

The numeral 1 indicates an ordinary wagon box having detachably supported on 40 the upper edge thereof, in the customary manner, a top box 2.

The numeral 3 indicates the seat plank and the numeral 4 the folding back of the wagon seat. This back 4 is secured to the 45 seat plank 3 by a pair of arms 5, rigidly secured, at one of their ends, to the back 4 and pivotally secured, at their other ends, to the hinge lugs 6, attached to the rear longitudinal edge of the seat plank 3. The 50 arms 5 are of a length sufficient to support the back 4, when turned upward, quite a distance above the seat plank 3, and they are so arranged as to permit said back to be folded into flat engagement with the top 55 of the seat plank 3. Stop projections 7, integral with the hinge lugs 6, engage the

arms 5, when the back 4 is turned up, and limit the backward movement thereof.

For detachably supporting the wagon seat 3 from the wagon box 1, or for detachably 60 supporting the same from the top box 2 in different vertical adjustments, two different sets of hanger arms 8 and 9 are provided. Each of these sets comprises two pairs of arms, one pair of each set being located at 65 each end of the seat plank 3. The hanger arms 8 and 9 comprising each pair are rigidly connected, near their free or outer ends, by tie bars 10 and 11, respectively, and their inner ends are pivotally secured to the bottom of the seat plank 3, by hinge lugs 12 and 13, respectively. The four hinge lugs 12 are secured to the four corners of the seat plank 3, thus permitting the hanger arms 8 to be placed in inoperative positions 70 under the seat plank 3, as shown in Fig. 2, or in operative vertical positions at the ends of the seat plank 3, as shown in Fig. 1. The tie bars 11 are somewhat shorter than the tie bars 10 and hold the arms 8 close 75 enough together to permit the same to pass between the arms 9. To fold the hanger arms 8 from operative to inoperative positions and vice versa, it is necessary to first turn the hanger arms 9 into operative or 80 outwardly projecting positions, to permit the tie bar 10 to clear the same during the movement of the hanger arms 8. The hinge lugs 13 are secured to the under side 85 of the seat plank 3, at a sufficient distance 90 from the outer edge thereof to permit only the free end portions of the hanger arms 9 to project beyond the ends of the seat plank 3. The free ends of the arms 8 terminate in hooks 14, adapted to embrace the upper 95 edge portions of the top box 2, and support the wagon seat within the top box 2, with the seat plank 3 in substantially the same horizontal plane with the upper edge of the wagon box 1. The arms 9 are provided 100 with pairs of laterally spaced lugs 15, adapted to engage the opposite sides of the wagon box 1 or the top box 2, and thereby hold the arms 9 against endwise sliding movement on said boxes. For holding 105 either set of hanger arms 8 and 9 in inoperative positions under the seat plank 3, a pair of turn buttons 16 is mounted, for horizontal swinging movement, on a pair of depending studs 17, secured to the under side 110 of the seat plank 3.

Obviously, by means of the hanger arms

9, the seat plank 3 may be supported from the upper edge of the wagon box 1 in a position to permit a person sitting thereon to rest his feet on the bottom of said box; or, in 5 case the wagon box 1 is provided with a top box, as shown in Fig. 1 of the drawings, the wagon seat may be supported in substantially this same position, by suspending the same from the top box 2 by means of 10 the hanger arms 8. In case the wagon boxes 1 and 2 are filled with a load, the wagon seat may be supported above the load on the upper edge of the top box 2, by the hanger arms 9. After the load is 15 emptied, the seat may be lowered to a position within the wagon boxes, thus affording greater comfort for the driver.

What I claim is:

1. The combination with a wagon box, of 20 a seat, and two sets of hanger arms secured to said seat for supporting the same from said wagon box in different vertical adjustments, one set of said hanger arms being hinged to the bottom of said seat, inward of the 25 ends thereof, for movement to and from a horizontal operative position, and the other set of said hanger arms being hinged to the ends of said seat, for movement to and from a vertical operative position, substantially as described.

2. The combination with a wagon box, of 30 a seat, two sets of hanger arms secured to said seat for supporting the same from said

wagon box in different vertical adjustments, one set of said hanger arms being hinged to the bottom of said seat, inward of the 35 ends thereof, for movement to and from a horizontal operative position and the other set of said hanger arms being hinged to the ends of said seat, for movement to and from a vertical operative position, and means for locking either set of said arms in an inoperative position, substantially as described.

3. The combination with a wagon box, of 40 a seat, two sets of hanger arms secured to said seat for supporting the same from said wagon box in different vertical adjustments, one set of said hanger arms being hinged to the bottom of said seat, inward of the 45 ends thereof, for movement to and from a horizontal operative position and the other set of said hanger arms being hinged to the ends of said seat, for movement to and from a vertical operative position, said hanger arms being adapted to be turned into inoperative 50 positions under said seat, and means for locking either set of said arms in an inoperative position, substantially as described.

In testimony whereof I affix my signature in presence of two witnesses:

LOUIS A. LARSON.

Witnesses:

CLYDE W. LONG,
J. W. CURTIS.
